UNITED STATES PATENT OFFICE

ALFRED W. F. GUEST, OF BROOKLYN, NEW YORK, ASSIGNOR TO MERGENTHALER LINOTYPE COMPANY, A CORPORATION OF NEW YORK

TYPOGRAPHICAL DISTRIBUTING MACHINE

Application filed October 1, 1930. Serial No. 485,632.

This invention relates to typographical distributing machines, such as linotype machines of the general organization represented in Letters Patent of the United States to O. 5 Mergenthaler, No. 436,532, wherein circulating matrices are released from a magazine in the order in which their characters are to appear in print and then assembled in line, the composed line transferred to the face of 10 a slotted mold, the mold filled with molten metal to form a slug or linotype against the matrices which produce the type characters thereon, and the matrices thereafter returned through distributing mechanism to the magazine 15 from which they started.

In their circulation through the machine, the matrices are supported at times by distributing teeth formed in a thin web portion located at their upper ends, and at other times 20 by means of projecting ears located at their opposite edges, two at the top and two at the bottom. Ordinarily in the case of a wide or thick matrix, the distributing teeth are located at one side of the matrix, while the 25 projecting ears (all in the same plane) are located at the opposite side of the matrix. As a result of such off-center location of the projecting ears, these wide or thick matrices when supported by their upper ears alone 30 have a tendency to, and they actually do, rock or tilt about their upper ears as a fulcrum and hang slantwise from the supporting rails of the organ which at the time is carrying them.

35 This objectionable condition becomes more pronounced during the transfer of the composed line from the first elevator into the upper transfer channel, when the matrices are supported in the first elevator solely by their 40 upper projecting ears and are obliged to present their distributing teeth in line with the ribbed bar of the second elevator. It frequently happens that, at this time and for the reasons stated, the matrices are so badly 45 slanted that their distributing teeth are located altogether too low to engage the ribbed bar of the second elevator and hence are left behind when the second elevator ascends to deliver the matrices to the distributing mechanism proper. As a result, the matrices are 50

swept out of the upper transfer channel along with the spacebands and are either improperly delivered to the spacer magazine, or are spilled into the machine, giving rise to considerable annoyance, inconvenience and delays. 55

The present invention is intended to overcome these and other objections and contemplates the provision of means for maintaining the matrices in an upright or erect position during their transfer from the first elevator into the upper transfer channel and onto the second elevator bar. In the embodiment illustrated, these means are in the form of a pair of spring-actuated plates or detents 60 located at the entrance of the upper transfer channel and arranged to engage the lower projecting ears of the matrices during transfer. In this way, even though any of the 65 matrices may hang slantwise in the first elevator, they will be straightened up under the influence of the spring-actuated plates or detents as they enter the upper transfer channel and before their distributing teeth reach the ribbed bar of the second elevator. As a 70 result the distributing teeth of the matrices will be properly aligned with the ribs on the second elevator bar and thus guided accurately into engagement therewith. 75

It is recognized that the scheme of straightening up the matrices during transfer is broadly old, being disclosed in the Muehleisen Patent No. 1,645,615, dated October 18, 1927. However, the present invention constitutes a valuable improvement over 80 this prior patented arrangement for several reasons. In the first place, the spring-actuated plates or detents herein proposed are much simpler to manufacture and install, and in the second place, they are more efficient, and particularly since they act on the 85 matrices successively during transfer instead of only on the leading matrix of the composed line.

90 Referring to the drawings:

Fig. 1 is a front elevation of a portion of a linotype machine showing the invention as applied thereto;

Fig. 2 is an enlarged sectional view showing a composed line in process of transfer 100

from the first elevator into the upper transfer channel;

Fig. 3 is a diagrammatic view depicting a slanted matrix and the manner in which the 6 spring-actuated plates or detents cooperate therewith;

Fig. 4 is a similar view showing the slanted matrix of Fig. 3 as having been straightened up by the spring-actuated plates or detents; and

Fig. 5 is a detail view taken on the line 5—5 of Fig. 2.

The line of matrices X and spacebands Y, after being composed, is transferred to the 15 first elevator A and later, after casting, carried up by that elevator into registration with the upper transfer channel B, which at the time contains the ribbed bar C¹ of the second elevator C, all as shown in Figs. 1 and 2. 20 In this condition of the parts, a line transfer carriage D is operated to shift the composed line out of the first elevator and into the upper transfer channel, the matrices X being expected by virtue of their distributing 25 teeth X¹ to pass into engagement with the ribbed bar C¹ of the second elevator, and the spacebands Y being expected (because of the absence of distributing teeth) to clear the bar C¹ and become supported by their ears 30 Y¹ on the customary rails of the upper transfer channel. Thereafter the second elevator C ascends to deliver the matrices to the distributing mechanism proper, leaving the spacebands behind to be transferred to their 35 storage magazine by a spaceband pawl or gripper not shown. The foregoing parts and their mode of operation are so well known that any further description would be superfluous.

40 As shown, the matrices X are provided with upper and lower pairs of projecting ears X² and X³, respectively, these ears being located at the right or leading side of the matrices while the distributing teeth X¹ are located at the left or following side of the matrices. In the case of the thicker matrices, the projecting ears are located well to one side of the center of gravity, and consequently when the matrices are supported 45 solely by their upper projecting ears X², as they are in the first elevator A from the customary rails A¹, they are free to assume a slanted or inclined position somewhat as indicated in Fig. 1, it being noted that in the raised position of the elevator shown the composed line is slack or loose due to the relaxation of the justifying spacebands Y. In such slanted position of the matrices, their distributing teeth X¹ are likewise slanted and 50 moreover (being remote from the fulcruming point of the upper ears) fall below the level of the ribbed bar C¹ of the second elevator, with the result that when the composed line is transferred from the first elevator 55 those matrices which are standing aslant at

the time will fail to engage the second elevator bar C¹ and hence will not be distributed.

In overcoming the foregoing objections, the upper transfer channel B is provided at its entrance with yielding means arranged to engage the matrices successively during their transfer from the first elevator A in order to maintain them in an erect or truly vertical position for proper engagement with the second elevator bar. The yielding means herein shown are constituted by a pair of spring-actuated plates or detents E arranged at the entrance of the upper transfer channel and in position to engage simultaneously with the outer edges of the lower projecting ears X³ of the matrices. While other forms might be suitable, the spring-actuated detents each comprise a bent plate presenting a main body portion E¹ slidable transversely in the side wall of the upper transfer channel, an outer portion E² adapted by its engagement with the outer face of the channel side wall to act as a stop in limiting the inward movement of the detent, and an inner matrix engaging portion E³ arranged in the path of the lower matrix ears X³ or just above the customary matrix supporting rails B¹ formed on the opposite side walls of the upper transfer channel at its entrance. To facilitate their engagement with and disengagement from the matrix ears, the detent portions E³ are beveled or rounded off at their opposite ends, as at e, leaving intermediate straight parallel portions e'. 90

95 Pressing outwardly on the detent portions E³ are comparatively strong compression springs E⁴ seated within recesses formed in the side walls of the upper transfer channel, it being obvious that the matrices to pass the detent portions must overcome the resistance of the springs by camming the detent portions backwardly or outwardly from the path of the matrices. 100

105 The action of the spring-actuated detents is graphically illustrated in Figs. 3 and 4. In the former figure, a wide matrix is shown as tilted toward the right and with its lower ears X³ about to engage the detents E. When such engagement takes place, the detents offer sufficient braking resistance to prevent the lower ears from passing, this braking resistance being continued until the matrix under the pushing influence of the transfer carriage D is rocked back about its upper ears X² as a fulcrum to an upright or vertical position (see Fig. 4), at which time it will lie flatly against the following matrix in the line or, if the matrix happens to be the last one in the line, flatly up against the matrix engaging plate of the transfer carriage (see Fig. 2). While the detents will continue to offer their braking resistance, the continued movement of the transfer carriage will force the leading matrix past the detents, camming them back as in Fig. 4. The extent 110

115 120

125 130

of the straight parallel portions e^1 of the detents is such that the distributing teeth of the matrix acted on will become engaged with the ribbed bar C^1 of the second elevator before the matrix clears the detents. In this way any matrix subject to slanting, without regard to thickness, will be maintained in an upright or erect position during its transfer from the first elevator to the second elevator.

10 It will be observed that, due to the stationary mounting of the spring-actuated detents, they are caused to engage all the matrices of the composed line in succession, acting first upon the leading matrix of the line as in Fig. 2, and then upon each succeeding matrix in turn as it leaves the first elevator and enters the upper transfer channel for engagement with the second elevator bar. Hence the maintenance of the individual matrices of a composed line in erect position during transfer is not dependent upon the preceding matrices, so that any looseness in the line which might take place after the leading matrices are carried past the detents will not interfere with the action of the detents in straightening up the following matrices as they become the leading ones. Moreover, by engaging each succeeding matrix at its opposite edges, the detents serve to prevent the individual matrices from turning or twisting about a longitudinal axis during transfer and thus insure the proper engagement of their distributing teeth with the second elevator bar. These and other advantages will be apparent to those skilled in the art.

It will now be appreciated that the novel arrangement herein shown and described constitutes a valuable and substantial improvement over the prior arrangement shown in the Muehleisen patent before referred to, being as before stated, not only easier and less expensive to manufacture and install, but in addition stronger and more durable and far more efficient in performing the required function of straightening up the matrices.

The invention has been shown only in preferred form and by way of example, but obviously many changes and variations therein and in its mode of application will readily suggest themselves to those skilled in the art without departing from the scope or spirit of the invention. It will be understood therefore that the invention is not limited to any specific form or embodiment except in so far as such limitations are specified in the appended claims.

Having thus described my invention, what I claim is:

60 1. In a typographical distributing machine equipped with matrices formed with projecting ears at their upper ends at one side of their center of gravity, the combination of a line transporter having rails upon which the matrices are supported by their upper

projecting ears, a second transporter to receive the matrices from the first, means for transferring the matrices from the first to the second transporter, and yielding means arranged in a fixed position to engage the 70 matrices successively during their transfer to maintain them in an erect position.

2. A combination as in claim 1, characterized by the fact that the yielding means therein referred to comprise a spring-actuated 75 plate or detent adapted to engage the lower ends of the matrices to straighten them up from a slanting position.

3. A combination as specified in claim 1, characterized by the fact that the yielding 80 means therein referred to are in the form of a pair of spring-actuated plates or detents adapted to engage the opposite edges of the matrices at their lower ends to straighten them up from a slanting position. 85

4. In a typographical distributing machine equipped with matrices formed at their upper ends with distributing teeth and with projecting ears located at one side of their center of gravity, the combination of a line 90 transporter having rails upon which the matrices are supported by their projecting ears, a second transporter to receive the matrices from the first, and comprising a ribbed bar to support the matrices by their distributing teeth, means for transferring the matrices from the first to the second transporter, and yielding means arranged in a fixed position to engage the matrices successively during their transfer to maintain 100 them in an erect position as their distributing teeth become engaged with the ribbed bar of the second transporter.

5. In a machine of the linotype class, the combination of a first elevator having rails 105 upon which the matrices are supported by their upper projecting ears, an upper transfer channel into which the composed line of matrices and spacebands is transferred, a second elevator having a ribbed bar to support the matrices by their distributing teeth, and yielding means located in a fixed position at the entrance of the upper transfer channel and arranged to engage the matrices successively at their lower ends during 115 transfer.

6. In a machine of the linotype class, the combination of a first elevator having rails upon which the matrices are supported by their upper projecting ears, an upper transfer channel into which the composed line of matrices and spacebands is transferred, a second elevator having a ribbed bar to support the matrices by their distributing teeth, and a spring-actuated plate or detent located 120 in a fixed position at the entrance of the upper transfer channel and arranged to engage the lower end of the leading matrix of a composed line to maintain it in an erect position during transfer. 130

7. In a machine of the linotype class, the combination of a first elevator having rails upon which the matrices are supported by their upper projecting ears, an upper transfer channel into which the composed line of matrices and spacebands is transferred, a second elevator having a ribbed bar to support the matrices by their distributing teeth, and a pair of spring-actuated plates or detents located in a fixed position at the entrance of the upper transfer channel and arranged to engage the lower projecting ears of the leading matrix of a composed line and maintain it in an erect position during transfer.

8. A combination as specified in claim 6, characterized by the fact that the spring-actuated plates therein referred to are located immediately above the supporting ledge or rails formed at the entrance of the upper transfer channel and upon which the lower ears of the matrices are supported during transfer.

9. A combination as specified in claim 7, characterized by the fact that the spring-actuated plates or detents therein referred to are slidable transversely in the side walls of the upper transfer channel and are provided with stop portions to limit the extent of their projection into said channel.

10. A combination as specified in claim 7, characterized by the fact that the spring-actuated plates or detents therein referred to are each formed at its matrix engaging portion with beveled or rounded ends to facilitate the cooperation of the plates or detents with the matrices.

11. A combination as specified in claim 7, characterized by the fact that the spring-actuated plates or detents therein referred to have matrix engaging portions of sufficient extent to maintain their engagement with the matrices until the distributing teeth of said matrices become engaged with the ribbed bar of the second elevator.

12. In or for a machine of the linotype class, an upper transfer channel provided at its entrance with a spring-actuated plate or detent arranged in position to engage the lower projecting ears of matrices entering said channel, as and for the purpose described.

In testimony whereof, this specification has been duly signed by:

ALFRED W. F. GUEST.
